(57) **CLAIM**

The ornamental design for a closed laptop computer, as
shown and described.

DESCRIPTION

The present application is related to U.S. Design patent
application Ser. No. 29/611,586, entitled Open Laptop Com-
puter, and to U.S. Design patent application Ser. No. 29/611,
591, entitled Tablet Computer, the entire disclosures of
which are incorporated herein by reference.

FIG. 1 is a front perspective view of a closed laptop computer according to a first embodiment of our design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top elevation view thereof;
FIG. 7 is a bottom elevation view thereof;
FIG. 8 is a rear perspective view thereof;
FIG. 9 is front perspective view of a closed laptop computer according to a second embodiment of our design;
FIG. 10 is a front elevation view thereof;
FIG. 11 is a rear elevation view thereof;
FIG. 12 is a right side elevation view thereof;
FIG. 13 is a left side elevation view thereof;
FIG. 14 is a top elevation view thereof;
FIG. 15 is a bottom elevation view thereof; and,
FIG. 16 is a rear perspective view thereof.

The broken lines showing portions of the closed laptop computer illustrate portions of the article and form no part

(Continued)

of the claimed design. The stippling shown on portions of the closed laptop computer illustrates a contrast in appearance.

1 Claim, 12 Drawing Sheets
